UNITED STATES PATENT OFFICE.

LAURENCE C. MALTBY, OF DAYTON, OHIO.

PISTON-VALVE FOR EXPLOSIVE-ENGINES.

1,110,635.

Specification of Letters Patent. Patented Sept. 15, 1914.

Application filed August 11, 1913. Serial No. 734,171.

To all whom it may concern:

Be it known that I, LAURENCE C. MALTBY, a citizen of the United States, residing at Dayton, in the county of Montgomery and State of Ohio, have invented a new and useful Improvement in Piston-Valves for Explosive-Engines, of which the following is a specification.

This invention relates to new and useful improvements in piston valves for explosive engines.

The object of the invention is to provide a simple, efficient and positively operated piston valve for engines of the explosive type. The valve is so constructed and arranged as to cause the gases to be readily and effectively admitted to and exhausted from the main cylinder, while at the same time adequate provision is made for an easy operation of the valve, with which the expansion and contraction of the latter might otherwise interfere.

In the accompanying drawings, Figure 1 is a sectional view of my improved piston valve connected to the engine cylinder. Fig. 2 is a section taken on the line $g-g$ of Fig. 1. And Fig. 3 is a detail view of a portion of one of the rings for the valve piston.

Throughout the specification and drawings, similar reference characters denote corresponding parts.

In a detailed description of my invention, 1 designates a cylinder of an explosive engine in which a piston 2 is movable. Passing through the piston 2 is a wrist pin 3 to which is connected a connecting rod 4 through which the main shaft of the engine is operated. A line 5 indicates the circle of rotation of the lower end of the connecting rod 4. Preferably cast integral with the cylinder 1 is a water jacket 6 for the purpose of cooling the former. The upper end of the cylinder is closed with the exception of a threaded aperture 7 adapted to receive an ignition plug 8.

Adjacent the cylinder 1 and cast integral therewith or otherwise constructed, as desired, is a valve cylinder or chest 9, which is likewise cooled by the water jacket 6. Communication is established between the cylinder 1 and valve chest 9, by ports 10 and 11, the port 10 being located slightly above the uppermost point of the stroke of the piston 2, while the port 11 is so located as to slightly clear the piston 2 at the lower-

most point of its stroke. The upper end of the cylinder 9 is open to an exhaust pipe.

Adapted to reciprocate within the cylinder 9 is a piston 12. Mounted on the lower end of said piston is a pitman 13 to which is pivotally connected a connecting rod 14 actuated from the main crank shaft in a predetermined ratio to the connecting rod 4, through mechanism not shown. To later explain this ratio, a line 15 is drawn indicating the circle of rotation of the lower end of the connecting rod 14.

The piston 12 is divided into two sections by a partition 16, the upper section of said piston being open to the cylinder 9 while the lower section is closed at its bottom. However, the lower section of said piston has a port 17 which is adapted to communicate with a port 17^a which passes through the cylinder 9 for connection with a supply pipe from the carburetor (not shown).

Surrounding the piston 12, one on either side of the partition 16, are split rings 18 and 19. The aperture 17 in the piston 12 continues through the ring 19 to permit the free passage of gas therethrough from the port 17^a. Also extending through the piston 12 and ring 19 is a port 20 adapted to register with the port 11, and extending through the piston 12 and ring 18 is a port 21 which is adapted to register with the port 10. It will now be seen that the rings 18 and 19 are wide enough to permit the ports 21 and 20 to extend through them.

In order that the rings 18 and 19 may be prevented from lateral movement, which would result in a partial or complete obstruction of the passage of gas through the ports 20 and 21, a pin and groove construction is provided, as shown in Figs. 2 and 3. Midway the vertical edge of each ring is a hollowed-out portion 22, said hollowed-out portions being circumferential and facing each other to receive a pin 23 set in the piston 12. The pin 23 prevents the rings 18 and 19 revolving around the piston 12 to completely or partially close the ports 20 and 21; in other words, it prevents the apertures forming these ports in the piston and rings working out of alignment.

The engine and valve pistons have the following relative movement: When the lower end of the connecting rod 14 of the piston 12 has the position a , the lower end of the connecting rod 4 of the piston 2 has the posi-

tion *e*. This is the relative position of the two rods and their corresponding pistons after the discharge of the gas from the cylinder 1, the ports 10 and 21, and 20 and 11 being out of alinement. When the lower end of the connecting rod 4 reaches the position *f*, the connecting rod 14 attains the position *b*, causing the ports 20 and 11 to register to permit the admission of gas therethrough into the engine cylinder 1. When the lower end of the connecting rod 4 again reaches the position *e*, the gas which has entered the cylinder 1 through the ports 20 and 11 will have been compressed by the upward movement of the piston 2, and a further admission of gas checked by reason of the piston 2 closing the port 11. When the piston 2 has reached its uppermost position, the lower end of the connecting rod 14 will have attained the position *c*. Ignition of the compressed gases within the cylinder 1 now takes place, the piston 2 is forced to its lowermost position by the resulting explosion and the lower end of the connecting rod 14 occupies the position *d*. As the piston 2 again moves upward, the lower end of the connecting rod 14 will be moved to its highest point between the points *a* and *d*. The movement of the lower end of the connecting rod 14 from the point *d* to its highest point, will bring the port 21 into alinement with the port 10, to permit the burned gases to escape through said ports into the piston 12 and thence through the upper end of the piston 12 into the exhaust pipe, as the engine piston 2 gradually moves upwardly.

In other piston valves, much trouble is experienced, and particularly in internal combustion engines, because of the unequal expansion and contraction of the piston 12 due to the action of the hot gases upon it. In my invention I take care of this problem by the provision of split rings 18 and 19, heretofore referred to. These rings are wide enough to permit the ports 20 and 21 to extend through them, and flexible enough to permit the piston 12 to have a free and easy movement through the cylinder 9 at all times. The rings are so constructed as to provide for the expansion of the piston 12 due to the action of the hot gases upon it, and still permit said piston to have a free and easy movement within the cylinder. These rings are not the narrow ones commonly used on other pistons, but are wide enough to be termed bands through which the ports 17, 20 and 21 extend. Were the rings so narrow as not to include the ports, much gas would be wasted that might otherwise be saved. Being split, the rings will expand to keep the ports tight at all times, which is absolutely essential to the proper

operation of an explosive engine. The water jacket 6 also assists in cooling the piston 12, as it surrounds a large portion of the cylinder containing the latter to permit the circulation of fluid around it.

I do not wish to be limited to the details of construction and arrangement herein shown and described, and the same may be varied to suit different conditions of use.

Having described my invention, I claim:

1. In an explosive engine, a main cylinder, a piston movable therein, a crank shaft driven by said piston, a valve cylinder adjacent to and connected with said main cylinder, a piston movable therein, ports in said valve piston, and split rings encompassing said valve piston through which said ports extend to closely communicate with corresponding ports in the main cylinder, each ring having a circumferential hollowed-out portion in each of its facing edges, said circumferential portions being located opposite each other, and a pin set in the valve piston and extending upwardly between said circumferential portions to prevent lateral movement of the ring, substantially as described.

2. In an internal combustion engine, a main cylinder, a piston movable therein, a main exhaust port in said cylinder located slightly above the uppermost point of the stroke of said piston, a main inlet port in said main cylinder located below the main exhaust port at a point to be opened by said main piston at the lowermost point of its stroke, a valve cylinder, a single valve piston movable therein, and inlet and exhaust ports in said valve piston adapted to register with their corresponding ports in the main cylinder as the valve piston is actuated, substantially as described.

3. In an internal combustion engine, a main cylinder, a piston movable therein, a main exhaust port in said cylinder located slightly above the uppermost point of the stroke of said piston, a main inlet port in said main cylinder located below the main exhaust port at a point to be opened by said main piston only at the lowermost point of its stroke, a valve cylinder, a crank-operated piston valve movable therein, and inlet and exhaust ports in said piston valve adapted to register with their corresponding ports in the main cylinder as the piston valve is actuated, substantially as described.

In testimony whereof I have hereunto set my hand this 8th day of August, 1913.

LAURENCE C. MALTBY.
